UNITED STATES PATENT OFFICE.

WILLIAM D. HAMERSTADT, OF INDIANAPOLIS, INDIANA.

METALLIC-SPIDERED FIBER PULLEY.

Application filed May 3, 1924. Serial No. 710,710.

To all whom it may concern:

Be it known that I, WILLIAM D. HAMERSTADT, a citizen of the United States, and a resident of Indianapolis, county of Marion, 5 and State of Indiana, have invented a certain new and useful Metallic-Spidered Fiber Pulley; and I do hereby declare that the following is a full, clear, and exact description thereof, reference being had to the accompanying drawings, in which like numerals refer to like parts.

This invention relates to a pulley of medium size and is of the character known as the metallic hub and metallic spidered 15 fibrous pulley.

The chief object of the invention is to construct a pulley of the general character indicated in an improved manner, whereby the resultant construction is manufactured 20 at a greatly reduced labor cost and whereby the material cost is materially reduced through the utilization of sheet metal spider-forming arms and their association with the fibrous portions forming the peripheral 25 pulley surface.

The chief feature of the invention consists in the construction of a metallic hubbed and metallic spidered fibrous pulley including a plurality of spider-forming arms 30 which are detachably associated with a hub and the fibrous portions for securing the latter to the former in fibrous pulley formation.

One feature of the invention consists in 35 forming spider-forming arms of sheet metal and associating a pair of said arms having aligned openings with a support for securing the fibrous pulley forming portions in pulley-forming formation upon the spider 40 arms.

Another feature of the invention consists in forming in the ends of said spider forming arms tubular portions which are adapted to support the fibrous pulley-forming portions in pulley formation.

Another feature of the invention consists in associating the desired number of spider-forming arms so that the base portions thereof form a substantially continuous hub supported portion while the arms extend outwardly therefrom and in spaced relation 50 with each other.

The full nature of the invention will be understood from the accompanying drawings and the following description and 55 claims:

In the drawings, Fig. 1 is a side elevational view of a fibrous pulley including a metallic hub and metallic spider-forming arms supporting the pulley portion upon the hub. 60 Fig. 2 is a sectional view taken on the line 2-2 of Fig. 1 and in the direction of the arrows and shows the parts in assembled relation and pulley formation. Fig. 3 is a front view of one of the spider-forming 65 arms. Fig. 4 is an end elevational view thereof. Fig. 5 is a view similar to Fig. 2 and illustrates one step in the assembly of the pulley-forming parts. Fig. 6 is a view similar to Fig. 5 and of a later step. 70 Fig. 7 is a view similar to Figs. 5 and 6 and of a still later step in the formation of the fibrous pulley.

In the drawings 10 indicates a metallic hub having a shaft opening 11, and herein 75 said hub is shown provided with a medianly positioned radially projecting flange 12, said flange at suitable intervals being provided with longitudinally positioned openings 13 which are in spaced and parallel relation 80 with each other.

Reference will be had to Figs. 3 and 4 wherein there is illustrated one of the spider-forming arms. Herein said arms are shown substantially keystone-shaped and include a 85 pair of edges 14 which are joined to a common arcuate edge 15 by the radial edges 16. In the portion of the plate defined by the arcuate edge, the radial edge and the adjacent edge, there is provided an aperture 17. Positioned medianly with respect to the plate, there is also provided another aperture 18 which herein is defined by a projecting sleeve or tube 19. Parallel to the edges 14, there is provided a raised or embossed portion 20. These embossments increase the strength and stiffness of the sheet metal spider-forming arm.

Reference will now be had to Figs. 1 and 2. The several spider forming arms are 100 substantially identical and are grouped in pairs as shown clearly in Fig. 2. A pair of spider-forming arms is herein illustrated as secured upon opposite sides of the median

peripheral edge 12 of the hub 10 by rivets or the like 21 passing through the opening 13 and registering openings 17 of adjacent spider-forming arms. As shown clearly in 5 Figs. 1 and 2, the hub-engaging portions of the adjacent spider-forming arms overlap. When in this position, the embossments extend outwardly from the flange 12 and the tubular portions 19 of the spider- 10 forming arms also extend oppositely and outwardly from each other. Herein but four spider-forming arms are illustrated, the number, however, may be increased and decreased at will, and the angles between the 15 edges 14 and 16 will vary according to the diameter of the pulley. Likewise the central angle determined by the arc will also vary, the latter decreasing as the size of the pulley increases, although this variation is not 20 necessary.

Reference will now be had to Figs. 5, 6 and 7. After the several arms have been secured together in spaced relation about the periphery of the hub, or prior thereto, if 25 desired, there is inserted between said parallel spider constructions the annular fibrous forming portions 23, each of which is apertured as at 24. When the desired width of material is interposed between the free ends 30 of the spider-forming constructions, a supporting pin 25 is positioned within the sleeve 19 and through the apertures 24 of the annular members 23, and thus the central portion of the pulley construction is 35 assembled, which construction is shown in Fig. 5. After the foregoing takes place, there is positioned upon opposite sides of the lateral support 25 a suitable number of 40 annular fibrous pulley-forming sections 23, the same having aligned openings 24 which are receivable by the lateral support. After they are positioned as shown in Fig. 6, they are compressed and as shown in Fig. 7 the 45 sleeve-forming portions 19 are forced into the openings 24 and the entire construction thus forms a substantially complete full width periphery from the outer parts of the last-mentioned pulley-forming sections. After the foregoing have been positioned, 50 the remainder of the pulley-forming sections are also positioned upon the support 25 and are pressed thereon. The peripheral surface thereafter may be operated upon to crown the same or otherwise fashion the 55 same as desired. If desired, the supports 25 may be tubular, and to said tubular lateral supports 25 may be secured end plates; although by the present process of manufacturing, such end plates or washers are 60 not necessary.

While the invention has been described in great detail in the foregoing specifications, the many modifications thereof which will readily suggest themselves to those

skilled in the art, are to be considered as illustrative and not restrictive in character, as outlined by the appended claims.

The invention claimed is:

1. A fibrous wheel including a hub, a plurality of radially projecting metallic arms, each terminating in a longitudinal and transversely extending sleeve, a pin positionable in said sleeve and projecting beyond the same for support purposes, and a plurality of annular fibrous and suitably apertured wheel-forming sections secured to the arms by the sleeves and pins seating in said apertures. 65 70 75

2. A fibrous wheel including a hub, a plurality of pairs of radially projecting metallic arms, each pair having aligned openings in their ends, a laterally projecting sleeve defining each opening, a support for each pair of arms and seatable in the sleeve defined openings, and a plurality of annular fibrous and suitably apertured wheel-forming sections secured between said arms and supported by said support. 80 85 90

3. A fibrous wheel including a hub, a plurality of pairs of radially projecting metallic arms, each pair having aligned openings in their ends, a laterally projecting sleeve defining each opening and extending oppositely from each other, a support for each pair of arms and seatable in the sleeve defined openings, and a plurality of annular fibrous and suitably apertured wheel-forming sections having a number thereof secured between said arms and supported by 95 100 105 said support and others positioned upon opposite sides of said arms and supported by said sleeve. 110

4. A fibrous wheel including a hub, a plurality of pairs of radially projecting metallic arms, each pair having aligned openings in their ends, a laterally projecting sleeve defining each opening and extending oppositely from each other, a support for each pair of arms and seatable in the sleeve defined openings, and a plurality of annular fibrous and suitably apertured wheel-forming sections having a number thereof secured between said arms and supported by 110 115 120 said support and others positioned upon opposite sides of said arms and supported by said sleeve, said lateral support projecting beyond said sleeves and other of said sections being positioned thereon. 125

5. A fibrous wheel including a hub, a plurality of pairs of radially projecting metallic arms, each pair having aligned openings in their ends, a laterally projecting sleeve defining each opening and extending oppositely from each other, a support for each pair of arms and seatable in the sleeve defined openings and projecting outwardly therefrom, and a plurality of annular fibrous and suitably apertured wheel forming sec-

tions secured upon opposite sides of said arms and supported by said sleeves and said support.

6. A fibrous wheel including a hub, a plurality of pairs of radially projecting metallic arms, each pair having aligned openings in their ends, a laterally projecting sleeve defining each opening and extending oppo-

sitely from each other, and a plurality of annular fibrous and suitably apertured 10 wheel-forming sections secured upon opposite sides of said arms and supported by said sleeves.

In witness whereof, I have hereunto affixed my signature.

WILLIAM D. HAMERSTADT.
